UNITED STATES PATENT OFFICE.

CLEVINGER A. EASTMAN, OF COLUMBIA, SOUTH CAROLINA.

DESIGN FOR A TEA-TRAY.

48,543.

Specification for Design.

Patented Feb. 15, 1916.

Application filed September 23, 1915. Serial No. 52,310. Term of patent 3½ years.

To all whom it may concern:

Be it known that I, CLEVINGER A. EASTMAN, a citizen of the United States, residing at Columbia, in the county of Richland, in the State of South Carolina, have invented a new, original, and ornamental Design for Tea-Trays, of which the following is a specification, reference being had to the accompanying drawing, forming a part thereof.

Figure 1 is a plan view of a tea tray illustrating my new design; Fig. 2 is a side view, and Fig. 3 an end view thereof.

I claim—

An ornamental design for a tea tray as shown.

Dated at Columbia, S. C., the 11th day of January, 1916.

CLEVINGER A. EASTMAN. [L. S.]
